COMBINED FILTER AND WATER TREATMENT
UNIT OR THE LIKE

Kouichi Watanabe, Toyonaka, Japan, assignor to Kurita
Water Industries Ltd., Osaka, Japan

Filed Sept. 28, 1971, Ser. No. 184,652

Term of patent 14 years

Int. Cl. D23—01

U.S. Cl. D23—3

FIG. 1

FIG. 2

FIG. 3

FIG. 4

FIG. 5

FIG. 6

FIG. 1 is a perspective view of a combined filter and water treatment unit or the like shown in my design;

FIG. 2 is a side view thereof;

FIG. 3 is a plan view thereof;

FIG. 4 is a front view thereof;

FIG. 5 is a back view thereof; and

FIG. 6 is a bottom view thereof.

I claim:

The ornamental design for a combined filter and water treatment unit or the like, as shown and described.
